US0D1102590S

(12) **United States Design Patent** (10) **Patent No.:** **US D1,102,590 S**
(45) **Date of Patent:** **** Nov. 18, 2025**

(54) **SYRINGE BARREL**

(71) Applicant: **DARCO International Corporation**,
Sunrise, FL (US)

(72) Inventor: **David A Ruben**, Sunrise, FL (US)

(73) Assignee: **DARCO International Corporation**,
Sunrise, FL (US)

(**) Term: **15 Years**

(21) Appl. No.: **29/925,451**

(22) Filed: **Jan. 24, 2024**

(51) **LOC (15) Cl.** **24-02**

(52) **U.S. Cl.**

USPC **D24/130**; D24/112

(58) **Field of Classification Search**

(57) **CLAIM**

The ornamental design for a syringe barrel as shown and described.

DESCRIPTION

FIG. 1 is a top, front right side isometric view of a syringe barrel, showing my new design;

FIG. 2 is a bottom, rear left side isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown are environmental only and form no part of the claimed design.

1 Claim, 5 Drawing Sheets
